ELECTRICALLY-CONTROLLED ELEVATOR.

No. 851,829.

Specification of Letters Patent.

Patented April 30, 1907.

Application filed April 16, 1906. Serial No. 311,888.

To all whom it may concern:

Be it known that we, CARL NAUJOKS and FREDERICK C. NAUJOKS, subjects of the Emperor of Germany, residing at San Francisco, in the county of San Francisco and State of California, have invented certain new and useful Improvements in Electrically-Controlled Elevators, of which the following is a specification.

10 This invention relates to improvements in electrically controlled elevators, the object of the invention being to provide an apparatus by which the elevator can be operated by the passengers themselves, either on the 15 several floors or in the elevator itself, and without the necessity of employing a special operator for that purpose.

Before describing in detail the construction of the apparatus, it may be desirable to 20 explain its general mode of operation. Supposing that the elevator is standing still at any floor of the building then the corresponding door of the elevator will, under those circumstances, be open. When a person on a 25 floor above or below desires to use the elevator, he presses an electric push button arranged on the frame work of the elevator, at the floor where he is standing. This withdraws a latch which holds the door open, and 30 allows the door to close, by a weight or a spring, as may be preferred. When the door closes, it closes a circuit through the motor, energizing the motor. The direction of the current permitted to pass through the motor 35 is made to depend upon whether a button above or below the elevator is pressed, so that in the former case the elevator moves up, and in the latter case it moves down. When it arrives at the floor at which the button was pressed, it breaks the circuit which 40 was closed through the motor, and also actuates a lever which opens the door, this door being then held open by the latch heretofore mentioned. A device then stops the elevator on a level with the floor. The passenger then steps into the elevator and presses a button in the elevator corresponding with the floor to which he desires to go, whether up or down. There will be a number of series of such buttons provided in the elevator, as, for instance, one series on each of the three sides of the elevator, so as to be within 45 easy reach of any passenger. The pressure

on this button closes the circuit which withdraws the latch which held the door open, so 55 that the door closes, and, in like manner as before, the closing of the door closing a circuit in the motor, the direction of the current through the motor being determined by the position of the floor corresponding to the button pressed. The elevator then ascends or descends to the desired floor and is arrested in the same manner as before, and the door is automatically opened.

Should a passenger on any floor press a 65 button when the elevator is moving toward him either from above or from below, this will automatically arrest the elevator and will automatically open the door. But should he press the button when the elevator 70 is moving away from him, this will have no effect upon its movement. Should there be a number of passengers on the different floors all wishing to enter the elevator, who press buttons on the elevator frame, the elevator, 75 if moving toward said passengers, will stop at each one in succession, and the door will automatically open. In like manner, should there be a number of passengers in the elevator wishing to leave the elevator on different 80 floors and who have pressed the corresponding buttons, the elevator will then stop in succession at the corresponding floors.

In the accompanying drawings, Figure 1 is a diagram of the apparatus; Fig. 2 is a 85 broken rear view of the elevator, showing one of the elevator doors in inside elevation; Fig. 3 is a side view of the elevator; Fig. 4 is a bottom plan view thereof; Fig. 5 is a diagrammatic view of the motor current check; 90 Fig. 6 is a side view of the regulator; Fig. 7 is a section of the grip; Fig. 8 is a broken perspective view of the inner ends of the current divider strips; Fig. 9 is a sectional view of one of said ends; Fig. 10 is a side view of a 95 break at a door; Fig. 11 is a vertical section thereof; Fig. 12 is a diagrammatic view, showing the modification of the apparatus as applied to a water-actuated elevator.

The electrical part of the apparatus comprises the following circuits:—First, the motor circuit, which must be closed in order to start the motor to move the elevator. This circuit is provided with means for changing the direction of the current through the armature, so as to change the direction in which 100

the motor is running. Second, a series of controller circuits, one for each floor, one effect of the closure of this controller circuit being to close the motor circuit to start the 5 motor. A second effect of each closure is to close the door safety circuit, should a door be open. Each such controller circuit has two branches, one leading to the main through the push button on the frame of the elevator 10 shaft for that floor, and the other leading to the main through a push button carried by the elevator and corresponding to the floor at which it is desired to stop. Third, a safety door circuit, which is a circuit passing in parallel through safety devices of the several doors of the elevator shaft, and then passing through a check-controlled device closed by the closure of the controller circuit of any 15 floor, so as to insure all doors closing before the elevator is started.

The controller circuit.—Leading from a wire 1 (hereinafter known as the third wire) connected with the positive main 2 of the positive and negative mains 2, 3, is a wire 4 20 which leads to all the push buttons 5 of the several floors of the elevator shaft. From the other side of each push button leads an individual wire 6 through a magnet 7 and thence by a wire 8 to one of two current dividing strips 9, 10, extending respectively to the bottom and top of the elevator shaft, and there being wound by springs 11 upon drums 12. The other ends of said strips 9, 10, which are adjacent to each other are carried 25 by the elevator. The end of the wire 8 is maintained in contact with one or the other of the contact strips 9, 10, by being connected to an individual plate 13 which is secured at any convenient point at the floor corresponding 30 to the push button, and has two spring metal lips 14, which at the middle are almost in contact with each other, but at the upper and lower edges flare outward from each other, so that either strip when passing 35 between said lips is maintained in close contact therewith by the pressure of the same. The ends of the strips which are adjacent to each other, are each made tapering or with a fine edge 16 as shown in Fig. 8, said edges being separated from each other to such a distance that the contact plate 13 can lie between them without being in contact with either, so that in this position there is no short circuit between the circuit dividing 40 strips, and the contact plate 13 is not connected with either strip. This is the position corresponding with the point at which the elevator should stop at each floor.

From the end of each current divider strip 45 is a wire 17 leading to a contact point 18 over which swings a direction changer 19 upon an arm 20 on a shaft 21 said shaft having a forked arm 22, the ends of which are pivoted to a friction grip 23 through which passes a 50 stationary cable 24 extending through the

shaft and secured at top and bottom. On one side of said grip extends posts 25 the ends of which are threaded and carry nuts 26 which press against a plate 27 by which plate is compressed a spring 28 the other end of which presses against a block 29 and forces said block against said cable 24, thus furnishing a uniform pressure of said grip upon said wire. When the elevator is moving, as, for instance, downward, the grip, on account of its frictional contact with the cable, lags 55 behind, causing the slotted forked arm to extend upward, and the direction changer to swing downward, and thus bringing it into contact with the contact point 18 connected with the lower current divider strip. The direction changer is connected by a wire 30 with the negative main 3. By this means all the electro-magnets of the floors below the elevator are placed in parallel upon a circuit 60 and leading through the push buttons 5, the current divider strip 9 and the direction changer, while those of the floors above the elevator are on a broken circuit. Consequently to close one of these circuits below 65 the elevator all that is necessary is to press the push button 5, whereupon the electro-magnet 7 is energized. However, any electro-magnet 7 of a floor below the elevator may also be energized by a circuit having a push 70 button in the elevator itself. For this purpose there is provided a wire 32 leading from the third wire 1 to a bar 33 adapted to contact with any one of a series of push buttons 34 each button 34 leading by a wire 35 to the 75 wire 6. The circuit then continues in the same way as before through the electro-magnet 7, contact 8, current divider strip 9 or 10 direction changer 19, wire 30, to the negative main 3. Thus upon pressing any 80 push-button 4 on a floor of the elevator shaft below the elevator, or on pushing any push button 34 in the elevator corresponding to a floor below the elevator, the corresponding electro-magnet 7 can be energized. The effect of energizing this magnet is to withdraw a latch 36, permitting a switch carrier 37 to swing, under the action of a spring 38. The movement of this switch carrier closes 85 two circuits, the motor circuit, and the door safety circuit.

The motor circuit.—The motor circuit is as follows:—From the positive main 2, by a wire 39, passing in series through breaks 40, one for each door of the elevator shaft, to the 90 top of said shaft, then returning by a wire 41, to a contact 42, arm 43 of the switch carrier 37, wire 44, to a contact 45 of a circuit changer 46, wire 47, (the parts from 42 to 47 being repeated for each floor of the shaft) 95 thence to a common wire 48 leading to a contact 49 on one side of the armature, through the armature 50, then by a contact 51 to a wire 52, connected at each floor of the elevator with a wire 53 leading to a contact 54 100

of the circuit changer, thence by a wire 55 to an arm 56 carried by the switch carrier, which, by the removal of said latch as aforesaid has been brought into contact with a contact 58, thence by a wire 59, to a common wire 60 leading to one end of the field magnet coil 61, through said coil, and then from the other end of said coil to the negative main 3.

The position of the circuit changer, depends upon the location of the elevator relative to the floor at which the circuit is thus closed. If the elevator is above said floor the current will be such that when the circuit is closed it will actuate the motor to cause the elevator to descend. If the elevator is below the floor at which the circuit is closed, then the current will be such that the motor will be moved in the direction causing the elevator to ascend. This is accomplished by means of a projection 62 extending from the side of the elevator, which, as the elevator passes, is adapted to contact with one or the other of two arms 63. When the elevator passes these arms in descending, this extension strikes the lower of the two arms and shifts the circuit changer from the position shown in the lower portion of Fig. 1 to the position shown in the upper portion of said figure. It will be readily seen that the electrical connections of the two wires 44, 55, with the two contacts 45 and 54 are now interchanged, so that the current proceeds through the armature in the opposite direction to that formerly taken.

The circuit changers are so situated that when the elevator stops at any floor, the projection 62 is midway between said arms 63. At that time, obviously, all the circuit changers below the elevator are in the position shown in the lower part of Fig. 1, and all the circuit changers above the elevator are in the position shown in the upper part of said figure. Consequently if a person in the elevator wishes to descend and energizes a magnet below him, or if a person on a floor below the elevator wishes to bring the elevator down, and presses the corresponding push button, thus energizing the corresponding magnet, the circuit will be closed in such a way as to operate the motor to bring the elevator down, and if a person in the elevator wishes to ascend and energizes a magnet above him, or if a person on a floor above the elevator presses the corresponding push button, the motor will be operated in the opposite direction. But it has been stated that the circuit through the motor passes in series through breaks, one at each door of the elevator shaft. Each break is open when the door is open and is closed when the door is closed, and it will therefore readily be seen that this circuit can not be closed, and the motor started, unless every door in the elevator shaft is closed.

Each break comprises a series, as four, of contact strips 64, each connected at sufficiently long intervals with a high resistance wire 65, these strips being secured upon the frame 66 of the shaft, adjacent to the door. Upon the door 67 itself is secured a bracket 70 for a contact arm 69 pivoted at 70 and carrying a spring contact 71. To a point 72 said arm 69 below its pivot is connected the lower end of a stretched spring 73, the upper end of which is connected to the top of a post 75 74 on said bracket. The effect of said spring is evidently to quickly throw the contact arm to one or the other side of the center. Upon the frame, in the path of the bottom of the arm 69, are provided stops 75, 76, and the 80 operation of this part of the device is therefore as follows:—Supposing that the door is being opened, by mechanism to be presently described, the contact arm will then extend from its pivot downward away from the 85 first of the series of contact strips, the contact spring will then pass in succession over the contact strips. Said contact strips and said resistance wire are connected with the wire 39 leading to the main 2, while the contact arm is connected with the wire 41 leading to the motor. As the contact spring moves over said strips in succession, it evidently throws more and more resistance into the circuit through the motor, causing the 90 current to diminish and checking the speed of the motor, so that when the door is fully opened the current through the motor is so slight that it is ready to stop. When the end of the arm 69 strikes the stop at that end of 100 its path, said stop causes said arm to swing across and when the stretched spring passes the pivot, said spring acts to throw the arm quickly past the center, and thus remove the contact spring 71 from the last contact strip 105 and break the circuit.

It being understood that the circuit through the motor will not be closed until all the doors in the elevator shaft are closed, it remains to be seen how any open door, particularly the one through which the passenger has just entered, or the one at the floor where the last passenger has left the elevator, is automatically closed upon pressing the push button. It will have been understood 110 that the direction changer which is quickly actuated by two springs on opposite sides is only tilted when the elevator is moved. When the elevator stops, said springs tend to move said direction changer into a horizontal 115 position. A regulator 77, the detailed construction of which will be presently described, is provided to regulate the time taken to bring the direction changer to this horizontal position. When it is in the horizontal position it is in contact with both of the current divider strips, so that when the elevator is at rest, and has been at rest for a sufficient length of time, all of the magnets of 120 all the floors are adapted to be energized by 125 130

the pressure of their respective corresponding door push buttons or elevator push buttons.

Supposing now that a person in the elevator has pressed the elevator push button corresponding to a floor beneath him, and that the result has been to close the circuit through the motor and so start the motor, the switch carrier of said floor beneath him 5 will have been shifted to close the circuits. This switch carrier is arranged at the elevator shaft close to the path of the rear side of the elevator, and is formed with sloping edges 78, 79, extending inwardly toward said path. Said edges, when the switch carrier has been swung inward, are adapted to contact with a projection 80 extending rearwardly from the elevator and to be pressed back thereby as the elevator passes, thereby 15 breaking the circuit through the motor, and stopping the motor. But before so doing, the switch carrier presses against one or the other (according as the elevator is ascending or descending) of two contact strips 81 and 20 thus closes a circuit 82 passing in parallel through two pairs of contact points 83, said circuit being derived from the wires 1 and 3, and passing through an electro-magnet 84 secured on the under side of the elevator. 25 This magnet then attracts an armature 85 against the tension of a spring 86 thereby withdrawing a latch 87 and releasing a lever 88 actuated by a spring 89, the other end of the lever carrying a fork 90, which fork is 30 thereby moved toward the front of the elevator shaft, so that one or the other rollers 91 carried on its members is in position to engage the arm 92 of a lever 93, pivoted at 94 and depresses the arm 93 thereby elevating 35 the other end of the lever, which is attached by cords 95 to arms 96 of bell crank levers 97 pivoted at 98, the other ends of the bell crank levers being attached by cords 99 to the edge of the door 67. Thus whether 40 either roller strikes the arm 92, in descending or ascending, the effect will be the same, to slide the door from the front of the elevator. It is by this motion that the door carrying the contact arm makes successive contacts 45 with the contact strips, and reduces the speed of the elevator before it is finally stopped by the outward movement of the switch carrier which breaks the circuit. The end of the lever 88 carries a roller 57 adapted 50 to engage one or the other of two cam blocks 100, which return the lever to its original position, it then being caught and held by the latch 87 of the armature which has been released from the electro-magnet 84. When 55 the door is withdrawn in the manner thus described, a latch 101 operated by a spring 102 moves in front of the front edge of the door and retains it open. This latch can be withdrawn by means of an electro-magnet 103 60 and the door allowed to swing forward and

close, which it will do by weights 104, or a spring might be provided for this purpose.

Safety door circuit.—But provision is made that the circuit through the electro-magnet will not be energized to withdraw the latch 70 until the door has been left open a sufficient length of time to enable a person in the elevator to pass out therefrom. Which is as follows:—When the door has been fully opened, a contact strip 105 carried at the 75 lower edge thereof electrically connects two points 106, 107, in a circuit leading from the wire 1 by a common wire 108 then by a wire 109 through the electro magnets 103, then through the contact points 106, 107, to a 80 common wire 110. This common wire is connected by a flexible wire 111 with a safety plate 112 carried upon the arm of the direction changer. When the elevator has just been arrested, the arm of the direction 85 changer is oblique to the horizontal, so that the safety plate is electrically separated from a contact point 113. But when the elevator has been at rest a sufficient time the safety plate is moved so as to make contact 90 with the contact point 113, the circuit then proceeding from said point by a wire 114 to a wire 115 common to all of the shafts, and thence by an individual wire 116 to a contact 117 which is adapted when the switch carrier swings inward to connect with a contact 118 on said switch carrier which contact is connected by an individual wire 119 with a common wire 120 leading to the wire 3. Consequently, even should a push button be pressed to start the motor, it will produce no effect until a sufficient length of time has elapsed since the opening of the door, for the motor circuit passes in series through all the breaks at the doors, so that if any 105 door is open the circuit is broken. But when the elevator has been at rest a sufficient length of time, the circuit through the magnet 103 controlling the latch 101 holding the door open is closed so far as the safety plate 112 and contact point 113 are concerned. It will still be open at all of the pairs of points 117, 118, on all of the switch carriers. But as soon as any person, by pressing a push button, moves said switch carrier, the door 110 controlling circuit is closed, the latch is withdrawn, and the door closes. The closing of 115 all open doors, if there are more than one open, closes all the breaks at the doors and closes the circuit through the motor. 120

The regulator.—In order to regulate the time elapsing from the stoppage of the door at any floor of the elevator shaft until it can be started again either by the immediate pressure of a button or because a button had 125 already been pressed before the stoppage of the elevator, there is provided on the shaft 21 of the arm 20 which carries the current direction changer and the safety plate, a ratchet wheel 123, which teeth are adapted 130

to be engaged by pawls 124 pivoted upon the 5 arm, opposite sides of the wheel, and controlled by cams 125 suitably supported upon the side of the elevator, said pawls being caused to normally engage said ratchet 10 wheels by springs 126. Geared to said ratchet wheel is a pinion 127 having a crank arm 128 pivotally connected to a rod 129 of a piston 130 sliding in a cylinder 131 the other 15 end of which is pivotally supported, as shown at 132, the ends of said cylinder being connected, past the piston, by a narrow tube 133 the passage through said tube being regulated by a valve 134. By screwing said 20 valve in or out the speed at which oil or other suitable fluid can pass from one of the cylinders to the other through said passage can be varied, and thus the speed at which the piston can move in the cylinder can be 25 varied. By this means can also be varied the time taken by the arm 20 to return to a horizontal or central position under the action of the springs. It is only when it has returned to this central position that the elevator can again be started. Stops 135 are 30 provided on each side of said arm 20 to limit the movement thereof. Thus the operation of this part of the apparatus is as follows:— Supposing that the elevator is descending, 35 the friction grip 23 will move upward relatively to the pivot of the arm, until arrested by the upper stop 135. The pawl carried thereby will not however engage the ratchet wheel, because its outer end will have engaged the cam 125, throwing the nose of the 40 pawl out of engagement with the ratchet wheel, so that the arm 20 can move freely upward. The other pawl can easily move over the teeth of the ratchet wheel. But as 45 soon as the elevator comes to rest, and the friction grip no longer lags behind, the springs 141 tend to swing said arm into a horizontal position, causing the pawl on the outer end of the arm to engage the ratchet 50 wheel, since the outer end of said pawl is not in engagement with its cam. Said arm can then only return slowly, since it is opposed by the pressure in the cylinder upon the piston due to the slow passage of the oil past 55 the valve.

Motor current check.—In this system the circuit through the motor is suddenly closed through the switch carrier, and this sudden closure of the circuit through the motor tends to burn out the coils of the motor, unless a rheostat or its equivalent is provided. To obviate this objection I provide the following contrivance. In one of the wires leading to the motor, as, for instance, the wire 3, is a 60 break which is closed by two circuits in parallel, of which one circuit 145 leads through a rheostat 146 and another circuit 147 leads through a small motor 148. This latter circuit is broken at two contact points 149 and 65 for connecting said points is an arm 150 of a

switch 151. This switch has a fork 152 between the members of which extends an arm 153 of a lever 154, the other arm of which is connected by a cord 155 with an arm of a pawl 156 the nose of said pawl engaging a 70 ratchet wheel 157, said ratchet wheel being connected to the shaft of the small motor. The arm 153 of the lever passes successively over contacts of the rheostat, its movement being resisted by a coiled spring 158. Upon 75 the rheostat is a magnet 159 supplied by branch wires 160 from the two wires 145. When there is no current through the wires leading to the main motor, this magnet is de-energized, and the lever 154 is drawn back 80 by the spring 158 to the out of circuit point of the rheostat. This throws the switch 151 into such position that it closes the circuit 167 through the small motor. The result is that when the circuit is closed through the 85 main motor except for this break a current passes through the small motor and starts it revolving, causing the ratchet wheel to revolve and to carry with it the pawl 156 and its arm 155 attached by the cord to the lever 90 154 and causing the lever to pass successively over the contact points of the rheostat, cutting out the successive resistances of the rheostat so that a greater portion of the current can pass through the main motor. 95 When said arm has been revolved by the ratchet wheel into such position that all of the resistance of the rheostat has been cut out, an extension 162 of a pawl strikes a 100 stop 163 which throws a pawl out of engagement with the ratchet wheel. The spring 158 does not however retract the lever back to its original position on the rheostat, because the magnet 159 is energized holding 105 said lever in position to give a full current. At that time the arm of the lever has thrown the switch so as to break the circuit through the small motor.

Water lift.—In Fig. 12 is shown a modification of the invention in which water power 110 may be used to operate the elevator, the control of said power being effected by electricity. For this purpose there is provided a supply pipe 170, a discharge pipe 171, and a lifting pipe 172, all controlled by a valve 173, adapted 115 in one terminal position to admit the water from the pipe 170 to the pipe 172 and in another terminal position to admit the water from the pipe 172 to the pipe 171, and closing all the pipes when in its intermediate position. This valve is moved by means of a pulley 174 driven from either of two motors 175, 176. The motor 175 receives its current by the main wire 177, the current then passing by a wire 178 to the several floors of 120 the shaft and then returning by a wire 179 in precisely the same manner as by the wires 60 and 39, in the former modification, said wire 179 being connected to a contact carrier 125 having a contact 181 adapted to be in 130

connection with a plate 182 when the elevator is at rest, a wire 183 leading from said plate to the main 184. Therefore, when the elevator is at rest, and the circuit between the wires 178 and 179 is closed in precisely the same manner as was the circuit between wires 60, 39 in the former modification, the motor 175 is started causing the valve 173 to turn and connecting the pipe 172 either with the pipe 170, or with the pipe 171, this depending upon the direction in which the motor is revolved. This direction will be controlled by the circuit changer wires 185, 186 which correspond precisely to the wires 52, 48, in the former modification. Supposing, for the sake of illustration, that the valve is turned to admit the water to raise the elevator, and that the contact carrier swings to the right into the position shown in the figure, then, after the valve has been sufficiently opened, the circuit through the motor 175 is broken, and the elevator continues on its upward motion, by reason of the admission of water into the pipe 172, until the valve is started on its return movement. This is accomplished by means of the second motor 176, which derives its current as follows:—from the wire 177 by a wire 188, contact 189, contact plate 190, wire 191, armature of the motor 176, wire 192, contact plate 193, contact 194, wire 195, field magnet of the motor, wire 196, through one of a series of individual wires 197, individual contact 198, contact plate 199 on the side of the elevator, switch carrier 200, actuated precisely in the same manner as the switch carrier in the first modification, individual wire 201, common wire 202, to the other main wire 184. Therefore when any push button, either on the elevator or at a floor of the shaft, has been pressed to cause the switch carrier to swing inward toward the path of the elevator, then when said elevator arrives at the position corresponding to said push button, the circuit is closed through the stopping motor 176, and the valve is returned to its central position, shutting off the water from the uplift pipe. A precisely similar operation takes place when the elevator is caused to descend by the flow of water from the uplift pipe into the discharge pipe, except that the contacts 189, 194 are now connected with plates 203, 204, connected by wires 205, 206, with the wires leading to the armature in such a manner that the direction of the current through the motor is reversed.

I claim:—

1. In an elevator, in combination with means for raising and lowering the elevator, a controller circuit for controlling said means, comprising an electro-magnet, a circuit therethrough, circuit divider strips having adjacent ends connected to the elevator and extending respectively downward and up-

ward therefrom, either of which is adapted to form a part of the circuit, means whereby said strips are electrically separated from each other when the elevator is in motion and are connected electrically only after the elevator has come to rest, and means at each floor on the elevator shaft for closing said circuit, substantially as described.

2. In an elevator, in combination with means for raising and lowering the elevator, a controller circuit for controlling said means, comprising an electro-magnet, a circuit therethrough, circuit divider strips having adjacent ends connected to the elevator and extending respectively downward, and upward therefrom, either of which is adapted to form a part of the circuit, means whereby said strips are electrically separated from each other when the elevator is in motion and are connected electrically only after the elevator has come to rest, and means carried with the elevator for closing said circuit, substantially as described.

3. In an elevator, in combination with means for raising and lowering the elevator, a controller circuit for controlling said means, comprising an electro-magnet, a circuit therethrough, circuit divider strips having adjacent ends connected to the elevator and extending respectively downward and upward therefrom, either of which is adapted to form a part of the circuit, means whereby said strips are electrically separated from each other when the elevator is in motion and are connected electrically only after the elevator has come to rest, means for regulating the time after the elevator comes to rest when said strips are electrically connected, and means at each floor on the elevator shaft for closing said circuit, substantially as described.

4. In an elevator, in combination with means for raising and lowering the elevator, a controller circuit for controlling said means, comprising an electro-magnet, a circuit therethrough, circuit divider strips having adjacent ends connected to the elevator and extending respectively downward and upward therefrom, means for winding up the end of either strip as the elevator moves toward said end, either of which is adapted to form a part of the circuit means whereby said strips are electrically separated from each other when the elevator is in motion and are connected electrically only after the elevator has come to rest and means at each floor on the elevator shaft for closing said circuit, substantially as described.

5. In an elevator, in combination with means for raising and lowering the elevator, a controller circuit for controlling said means, comprising an electro-magnet, a circuit therethrough, circuit divider strips having adjacent ends connected to the elevator and ex-

tending respectively downward and upward therefrom, either of which is adapted to form a part of the circuit, means whereby said strips are electrically separated from each other when the elevator is in motion and are connected electrically only after the elevator has come to rest comprising a cable, a friction device carried by the elevator, and a contact plate connected with said friction device, and means at each floor on the elevator shaft for closing said circuits, substantially as described.

6. In an elevator, in combination with means for raising and lowering the elevator, a controller circuit for controlling said means, comprising an electro-magnet, a circuit therethrough, circuit divider strips having adjacent ends connected to the elevator and extending respectively downward and upward therefrom, means for winding up the end of either strip as the elevator moves toward said end, either of which is adapted to form a part of the circuit means whereby said strips are electrically separated from each other when the elevator is in motion and are connected electrically only after the elevator has come to rest, said means comprising a controlling device permitted to move easily from its central position outward in any direction while variably restrained in its return movement, and means at each floor on the elevator shaft for closing the said circuit, substantially as described.

7. In an elevator, in combination with means for raising and lowering the elevator, a controller circuit for controlling said means, comprising an electro-magnet, a circuit therethrough, circuit divider strips having adjacent ends connected to the elevator and extending respectively downward and upward therefrom, means for winding up the end of either strip as the elevator moves toward said end, either of which is adapted to form a part of the circuit means whereby said strips are electrically separated from each other when the elevator is in motion and are connected electrically only after the elevator has come to rest, said means comprising a controlling device permitted to move easily from its central position outward in any direction while variably restrained in its return movement, and means at each floor on the elevator shaft for closing the said circuit, substantially as described.

8. In an elevator, in combination with means for raising and lowering the elevator, a controller circuit for controlling said means, comprising an electro-magnet, a circuit therethrough, circuit divider strips having adjacent ends connected to the elevator and

extending respectively downward and upward therefrom, means for winding up the end of either strip as the elevator moves toward said end, either of which is adapted to form a part of the circuit means whereby said strips are electrically separated from each other when the elevator is in motion and are connected electrically only after the elevator has come to rest, said means comprising a controlling device permitted to move easily from its central position outward in any direction while variably restrained in its return movement, and means at each floor on the elevator shaft for closing the said circuit, and consisting of a cylinder, a piston moving therein and an operative connection between said piston and the friction device brought into use only upon the return movement of the latter operative connection in closing, a ratchet wheel, pawls either of which is adapted to engage and advance the ratchet wheel when moving in one of its directions but passing freely over the same in the other direction, cams for disengaging said pawls when said operative connection is moving from its central to its outer position, a gear wheel moving with the ratchet wheel and a pinion geared thereto, and an operative connection between the piston and pinion, substantially as described.

9. In an elevator, in combination with means for raising and lowering the elevator, a controller circuit for controlling said means, comprising an electro-magnet, a circuit therethrough, circuit divider strips having adjacent ends connected to the elevator and extending respectively downward and upward therefrom, either of which is adapted to form a part of the circuit, means whereby said strips are electrically separated from each other when the elevator is in motion and are connected electrically only after the elevator has come to rest, and means at each floor on the elevator shaft for closing said circuit, one side of said circuit having two branches, a push button at the floor of the elevator shaft corresponding with the magnet in one of said branches, and a push button in the elevator in the other branch substantially as described.

10. In an elevator, the combination of a circuit for controlling the movement of the elevator, said circuit passing in series through a break at each floor of the shaft adapted to be closed by the corresponding door when closed, said circuit having branches, one for each floor of the shaft, each such branch having a break therein means actuated by the elevator moving past any floor for changing the direction of the motive power set in action by the closing of the motor circuit at that floor, and means at each floor for closing the corresponding latter break, substantially as described.

11. In an elevator, the combination of a circuit through the motor, one side of said circuit having branches, one for each floor of the elevator and each such branch having a break therein, said circuit then passing through a series of breaks, each adapted to be closed by the closing of the corresponding door at that floor, and means for closing the first break at any floor, operable from said floor, including a double switch, and a branch through the armature of the motor connected with said double switch, said double switch adapted to be moved by the elevator when passing, substantially as described.
12. In an elevator, the combination of a motor a circuit therethrough, a switch carrier at each floor of the shaft, having a switch, one side of the circuit through the motor being connected in parallel with all of said switches, a wire connected in parallel with the other side of the switch, said wire leading through a series of breaks one at each door of the elevator shaft and adapted to be closed by the closing of said door, a latch for holding said switch open, an electro-magnet for breaking said switch to permit it to close, and means for closing said magnet at the corresponding floor of the elevator shaft, substantially as described.
13. In an elevator, the combination of a motor, a circuit therethrough, a switch carrier at each floor of the shaft, having a switch, one side of the circuit through the motor being connected in parallel with all of said switches, a wire connected in parallel with the other side of the switch, said wire leading through a series of breaks one at each door of the elevator shaft and adapted to be closed by the closing of said door, a latch for holding said switch open, an electro-magnet for breaking said switch to permit it to close, and means for selectively energizing said magnet from the elevator, substantially as described.
14. In an elevator, the combination of a motor, a circuit therethrough, a switch carrier at each floor of the shaft having a switch, one side of the circuit through the motor being connected in parallel with all of said switches, a wire connected in parallel with the other side of the switch, said wire leading through a series of breaks one at each door of the elevator shaft and adapted to be closed by the closing of said door, a latch for holding said switch open, an electro-magnet for breaking said switch to permit it to close, a push button at the corresponding floor of the shaft in one side of the circuit through the magnet, a break in the other side and a device for closing said break when the elevator is moving toward said floor, and for opening said break when moving away therefrom, substantially as described.
15. In an elevator, the combination of a motor a circuit therethrough, a switch carrier at each floor of the shaft having a switch, one side of the circuit through the motor being connected in parallel with all of said switches, a wire connected in parallel with the other side of the switch, said wire leading through a series of breaks one at each door of the elevator shaft and adapted to be closed by the closing of said door, a latch for holding said switch open, an electro-magnet for breaking said switch to permit it to close, a latch for holding each door open, an electro-magnet for withdrawing said latch, a circuit through said electro-magnet, and means whereby said circuit is broken and the withdrawal of the latch rendered impossible until after the elevator has been at rest a predetermined period of time, substantially as described.
16. In an electric elevator, a motor check comprising, in combination with the main motor, a rheostat, a small motor, one of the wires leading to the main motor having a break closed by two circuits in parallel, of which one circuit leads to the rheostat and the other leads through the small motor, the latter circuit having a break therein, a switch for closing said break, a lever having an arm passing successively over contacts of the rheostat, said lever being operatively connected with said switch, and a spring resisting said movement, substantially as described.
17. In an electric elevator, a motor check comprising, in combination with the main motor, a rheostat, a small motor, one of the wires leading to the main motor having a break closed by two circuits in parallel, of which one circuit leads to the rheostat and the other leads through the small motor, the latter circuit having a break therein, a switch for closing said break, a lever having an arm passing successively over contacts of the rheostat, said lever being operatively connected with said switch, and a spring resisting said movement, and means for moving said lever from the revolution of the small motor, a magnet on a branch parallel with the circuit through the rheostat, said magnet being adapted to hold said lever when energized, substantially as described.
18. In an electric elevator, in combination with an elevator, a series of elevator doors, an electric circuit, and a motor in said circuit for operating the elevator, a series of resistances arranged to be successively thrown into said circuit by the opening of an elevator door to diminish the current therein and check the speed of the motor, substantially as described.
19. In an electric elevator, in combination with an elevator, a series of elevator doors, an electric circuit, and a motor in said circuit for operating the elevator, a series of resistances arranged to be successively thrown into

said circuit by the opening of an elevator door to diminish the current therein and check the speed of the motor, and means whereby, when the door is fully thrown open, said circuit is opened at said break, substantially as described.

In witness whereof we have hereunto set

our hands in the presence of two subscribing witnesses.
